UNITED STATES PATENT OFFICE.

JOHN EDWARD OGDEN, OF CORNWALL, NEW YORK.

BOLT-ANCHOR.

1,365,945.

Specification of Letters Patent. Patented Jan. 18, 1921.

Application filed September 5, 1919. Serial No. 321,739.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Bolt-Anchors, of which the following is a specification, reference being had to the accompanying drawings, 10 forming a part thereof.

This invention relates to bolt anchors of the general type disclosed in prior patents of mine, for instance, Patent No. 1,305,001 of May 27, 1919, in which the shell or shield 15 is constructed of sheet metal. The objects of the present invention are to improve on such prior structures, particularly in regard to securing a more firm and positive gripping effect, to simplify the parts and reduce 20 the cost.

Briefly the invention comprises a shield member which is made of sheet metal of substantially uniform thickness and of which the overall thickness is increased by 25 means of integral corrugations or protuberances offset from the body of the shell. Another feature of the invention is a special construction of expanding collars made also preferably of sheet metal and having 30 tapering external ridges formed by corrugating the metal of the collars to provide wedges for expanding the shell.

These and other objects of the invention will appear in the following specification 35 in which I will describe the invention, the novel features of which will be set forth in appended claims.

Referring to the drawings:

Figure 1 is a longitudinal sectional elevation of the complete bolt anchor, the section being taken on the line 1—1 of Fig. 2.

Fig. 2 is a similar sectional view at right angles to the plane of the Fig. 1, as on the line 2—2 of Fig. 1.

Fig. 3 is a longitudinal elevation partly in section of the shell alone.

Fig. 4 is an end view of the shell.

Fig. 5 is a transverse sectional view of the same, the section being taken on the line 5—5 of Fig. 3.

Fig. 6 is a top plan view of one of the expanding collars.

Fig. 7 is a bottom plan view of the same.

Figs. 8 and 9 are end views of the anchor 55 illustrating the manner in which it expands.

Figs. 10 and 11 are similar views illustrating the expansion of a three-part shield member.

Fig. 12 is a detail part sectional view of a shell having embossments of modified forms.

Fig. 13 is a longitudinal sectional view of another modification.

Fig. 14 is a cross sectional view of the same on substantially the plane of line 14—14 of Fig. 13.

Like characters of reference designate corresponding parts in all the drawings.

In the construction illustrated in Figs. 1 to 9, the shell, which is shown as made of relatively heavy gage sheet metal, is formed in two parts or halves, 20, 21 shaped to provide the flaring open ends 22 to receive the externally tapered expanding collars 23, 24.

The embossments consist in this first form, of a series of outwardly pressed corrugations 25 providing external longitudinally extending ribs 26. These ribs substantially correspond in height to the largest diameter of the flaring mouth portions of the shell, as clearly shown in Figs. 1, 3 and 4 so that the structure is of substantially the same outside diameter throughout its length. These ribs furthermore, are preferably substantially rigid and non-collapsible under pressure, they being for this purpose preferably formed in the shape of self-sustaining open arches as indicated in Fig. 4, capable of withstanding the compression forces to which they may be subjected in use.

The expanding collars are shown also as constructed of sheet metal and formed each in a single piece. These collars are made with a substantially cylindrical internal bore or bolt passage and the outer taper is provided by means of integral outwardly pressed corrugations 27 which taper in height from the outer ends of the collar toward the inner ends of the same. These tapering ribs or corrugations also are formed to be self-sustaining and non-collapsible.

One of the collars, 24, is shown as internally screw threaded to act as a nut for the bolt, it being made of metal sufficiently heavy to take such threads.

From the structure thus far disclosed, it will be evident that when the anchor is inserted in its seat and the bolt turned into the nut, the two expanding devices will be drawn toward each other and by reason of their

tapered construction will force apart the two sections of the shell, causing the external ribs or embossments on the shell parts to bite into and firmly engage the surrounding material. The open-arch or truss configuration of the ribs on both the shell and the collars gives them the strength necessary to resist collapse under pressure which will normally be applied.

10 To prevent turning of the collars while setting up the anchorage, I have shown the collars as provided with outwardly struck lugs 28 at their inner ends engaging inside the embossments formed in the shell. The 15 interlocking engagement of the elements also prevents separation of the parts when the bolt is not in place, it being understood that the sections of the shell are normally held together by the well-known interlocking parts or by encircling springs.

Another novel feature of the expanding collar is the construction of the same with the ribs which are in line with the central portions of the shell segments, of greater 25 height than the ribs at opposite sides of such ribs. These higher ribs follow up the sections as they are expanded, as indicated particularly at 29 in Fig. 9, so that when the anchorage is fully expanded the pressure is 30 equalized and borne by all the expanding ribs.

The structure disclosed in Figs. 10 and 11 is similar to the above, except that the shell in this case is made in three sections or segments, 30, 31 and 32. The operation, but for this matter of the division of the shell, is substantially the same as above described.

In Fig. 12, I have illustrated how the embossments of the shell may be relatively 40 short and may be disposed transversely, spirally or at various angles to the axis of the shell. In this particular view, the embossments or protuberances are substantially star-shaped, the arms of the stars forming 45 as many different angles as may be desired. These embossments are all struck up from the general plane of the shell but some of them, 33, are shown as struck outwardly and others, 34, as struck inwardly, the first 50 in this case, forming anchorage elements for engagement with the surrounding material and the latter bearing on the bolt to brace and reinforce the shell.

In the construction illustrated in Figs. 13 55 and 14, all the embossments or ribs, 35, are directed inwardly. With this construction, when the bolt is tightened, the tapered collars 36, 37, as they are brought together and act as wedges by engagement with the inclined ends 38, of the ribs, spread or open 60 up the shell on the line of longitudinal separation, indicated at 39. In the illustration the parts are shown held together by flanging the ends of the shell over shoulders 65 provided on the collars, as indicated at 40.

What I claim is:

1. In a bolt anchor, a longitudinally divided shell comprising a plurality of segments of substantially uniform thickness and provided with rigid embossments increasing the overall diameter of the shell and expanding means engaged with said shell. 70

2. In a bolt anchor, a longitudinally divided shell of substantially uniform thickness and provided with embossments, said shell having outwardly flaring open ends and expanding devices engaged within said flaring open ends. 75

3. In a bolt anchor, a longitudinally divided shell of substantially uniform thickness and provided with embossments, and expanding collars engaged in the ends of said shell and provided with external longitudinally disposed corrugations of gradually reduced height. 80

4. In a belt anchor, a shell of substantially uniform thickness having outwardly flaring open ends and embossments between said ends substantially corresponding in height to the greatest external diameter of the flaring ends, and expanding means engaged in said flaring ends. 85

5. In combination, a shell of substantially uniform thickness divided longitudinally into separate segments to provide for transverse expansion of the same, and an expanding collar engaged in the end of said shell and having portions of progressively increasing radii in line with parts of the several segments intermediate the edges thereof. 95

6. In combination, a shell of substantially uniform thickness divided longitudinally into separate segments to provide for transverse expansion of the same, and an expanding collar in the end of said shell and having portions of progressively increasing radii engaged with each of said segments. 105

7. In combination, a two-part shell of substantially uniform thickness divided longitudinally into separate halves to provide for transverse expansion of the same, an expanding collar engaged in the end of said shell having its outer side substantially parallel with its axis in one plane but tapered on lines away from said plane and disposed with said plane in line with the line of separation between the halves. 110

8. In combination, a shell of substantially uniform thickness divided longitudinally into separate segments to provide for transverse expansion of the same, and expanding collars engaged in the ends of said shell, said collars having portions of progressively increasing radii substantially in line with portions of the several segments intermediate the edges thereof and one of said collars being provided with screw threads. 120

9. In combination, a shell of substantially uniform thickness divided longitudinally into separate segments to provide for trans- 125

verse expansion of the same, and an expanding collar engaged in the end of said shell having external longitudinal corrugations decreasing in height from the outer toward the inner end of the collar.

10. In combination, a shell of substantially uniform thickness divided longitudinally into separate segments to provide for transverse expansion of the same, an expanding collar engaged in the end of said shell having external longitudinal corrugations decreasing in height from the outer toward the inner end of the collar to provide wedging ridges and having the ridges which are 15 in line with the more central portions of the segments of greater height than the remaining ridges.

11. As an article of manufacture, an expanding device for bolt anchors comprising 20 a one-piece sheet metal collar having a substantially cylindrical body provided with outwardly corrugated ridges tapering in height from one end toward the other end of the collar with two diametrically opposite 25 ridges of greater height than the others.

12. In a bolt anchor, a tubular shell having an external embossment near one end thereof and an expanding collar engaged in said end of the shell and provided with a 30 lug engaging inside the embossment to hold the collar within the shell and against turning in the shell.

13. In a bolt anchor, a substantially rigid sheet metal shield of substantially uniform 35 thickness divided longitudinally into segments, said segments having relatively rigid upstanding embossments and the shield having outwardly flaring open ends, expanding devices engaged in said open ends of the 40 shield and consisting each of a one-piece sheet metal collar having a substantially cylindrical body and outwardly corrugated ridges tapering in height from one end toward the other end of the collar to fit the 45 flaring ends of the shield, said collars having outwardly projecting portions near their

inner ends engaging the shield within said embossments.

14. In a bolt anchor, a substantially rigid sheet metal shield of substantially uniform 50 thickness divided longitudinally into segments having relatively rigid upstanding embossments and the shield having outwardly flaring open ends, expanding devices engaged in said open ends of the shield and 55 consisting each of a one-piece sheet metal collar having a substantially cylindrical body and outwardly corrugated ridges tapering in height from one end toward the other end of the collar to fit the flaring ends 60 of the shield and the ridges which are in line with the more central portions of the segments being of greater height than the ridges at the sides thereof to equalize the pressure on the shield after expansion of the 65 same.

15. An expansion bolt shield comprising a substantially rigid sheet metal shell of substantially uniform thickness divided longitudinally and provided with external up- 70 standing embossments, the shield having outwardly flaring open ends and said embossments decreasing in height as they approach said flaring ends.

16. An expansion bolt shield comprising 75 a substantially rigid sheet metal shell of substantially uniform thickness divided longitudinally and provided with external up- 80 standing embossments having parts extending longitudinally and parts extending transversely of the shield.

17. In a bolt anchor, a longitudinally divided shell having outwardly flaring end members and expanding members engaged therewith, certain of said members having 85 corrugated portions engaging the members and co-operating therewith.

In witness whereof I hereunto set my hand this 22nd day of August, 1919.

JOHN EDWARD OGDEN.

Witness:

I. B. MOORE.
